UNITED STATES PATENT OFFICE

168,314

WATER PISTOL

William R. McLain, Nashville, Tenn.

Application June 4, 1952, Serial No. 20,027

Term of patent 14 years

(Cl. D34—15)

To all whom it may concern:

Be it known that I, William R. McLain, a citizen of the United States, residing at Nashville, in the county of Davidson and State of Tennessee, have invented a new, original, and ornamental Design for a Water Pistol, of which the following is a specification, reference being had to the accompanying drawing forming a part thereof.

Figure 1 is a plan view from above of a water pistol embodying my new design;

Figure 2 is a side elevation of the water pistol illustrated in Figure 1;

Figure 3 is a plan view from below of the water pistol illustrated in Figure 1;

Figure 4 is a view in elevation of the front end of the water pistol shown in Figure 1; and

Figure 5 is a view in elevation of the rear end of the water pistol shown in Figure 1.

I claim:

The ornamental design for a water pistol, substantially as shown.

WILLIAM R. McLAIN.
